US00D828321S

(12) **United States Design Patent** (10) **Patent No.:** **US D828,321 S**
Yeom (45) **Date of Patent:** **** Sep. 11, 2018**

(54) **FLEXIBLE SMART MOBILE PHONE**

(71) Applicant: **Lenovo (Beijing) Co., Ltd.**, Beijing (CN)

(72) Inventor: **Jihun Yeom**, Beijing (CN)

(73) Assignee: **Lenovo (Beijing) Co., Ltd.**, Beijing (CN)

(**) Term: **15 Years**

(21) Appl. No.: **29/627,821**

(22) Filed: **Nov. 29, 2017**

Related U.S. Application Data

(62) Division of application No. 29/563,416, filed on May 4, 2016.

(30) **Foreign Application Priority Data**

(57) **CLAIM**

The ornamental design for a flexible smart mobile phone, as shown and described.

DESCRIPTION

FIG. 1 is a perspective view of a flexible smart mobile phone showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof shown in first bending position;

FIG. 9 is a left side view of FIG. 8;

FIG. 10 is a perspective view thereof shown in second bending position; and,

FIG. 11 is a left side view of FIG. 10.

1 Claim, 8 Drawing Sheets
